UNITED STATES PATENT OFFICE

157,539

BICYCLE HUB

Jay Rosten, Brooklyn, N. Y.

Application March 19, 1949, Serial No. 1,493

Term of patent 14 years

(Cl. D90—12)

To all whom it may concern:

Be it known that Jay Rosten, a citizen of the United States of America, residing at Brooklyn, New York, in the county of Kings and State of New York, has invented a new, original, and ornamental Design for a Bicycle Hub, of which the following is a specification; reference being had to the accompanying drawing, forming part thereof.

Figure 1 is a perspective view of a bicycle hub, showing my new design.

Figure 2 is a plan view thereof.

Figure 3 is an end view thereof.

I claim:

The ornamental design for a bicycle hub, as shown.

JAY ROSTEN.
